CHAIR

Henry E. Bennett, Grand Rapids, Mich.

Application March 13, 1936, Serial No. 68,588

6 Claims. (Cl. 155—179)

The present invention relates to chairs; and its object is, generally, to provide a chair having improved yielding means for supporting the occupant in comfortable positions; and more particularly, to provide such yielding means comprising a flexible sheet member and members for maintaining certain portions of the sheet member at different degrees of suspension than other portions thereof; and further, to provide such yielding means for supporting the weight of the occupant on the chair's seat; and further, to provide such yielding means for supporting the rearward pressure of the occupant on the chair's back; and further, to provide such weight-supporting and rear pressure-supporting means so combined that a comfortable support for the occupant is provided throughout; and further, to provide simple, economical and effective forms and specific constructions for attaining these ends.

These and any other and more specific objects hereinafter appearing are attained by, and the invention finds preferable embodiment in, the illustrative chair structure particularly described in the body of this specification and illustrated by the accompanying drawing, in which:

Figure 1 is an elevational side view of a chair, its flexible back and seat being shown in central vertical section taken on line 1—1 of Figure 2, illustrating the same in the position assumed when the chair is occupied;

Figure 2 is a view thereof in perspective with the back and seat in said position, certain parts being broken away;

Figure 3 is an elevational front view of one of the chair's rear posts with parts carried thereby illustrated in their position when the chair is occupied, the flexible back of the chair being shown in vertical section;

Figure 4 is a like view thereof but showing said parts and back in their position when the chair is unoccupied;

Figure 5, 6, 7 and 8 are sectional views of the same taken on horizontal planes corresponding to lines 5—5, 6—6, 7—7 and 8—8 of Figure 3 respectively;

Figures 9, 10 and 11 are vertical sectional views of the chair taken on vertical planes corresponding to lines 9—9, 10—10 and 11—11 respectively of Figures 2 and 12, illustrating the flexible seat and its supporting members;

Figure 12 is a top plan view of lateral side portions of the chair, the flexible seat being shown in section;

Figure 13 is an elevational inner side view of

lateral side portions of the chair illustrating a modified construction, the flexible sheet being shown in section;

Figure 14 is a transverse sectional view of lateral side portions of the chair illustrating means for adjusting the tension of the springs.

The main feature of my yielding support for the occupant of the chair is the provision of a flexible sheet member supported adjacent its lateral edges by a pair of elongated comparatively rigid members extending approximately parallelly with the lateral sides of the chair and mounted adjacent their corresponding ends for inwardly yielding or spring-resisted movement.

In the drawing is shown a chair having a base or frame including pairs of rear leg and back posts 1, front legs 2, horizontal lateral side rails 3 and horizontal front side and rear side rails 4, 5. The chair's seat 6 and back 7 are flexible sheet members of fabric, leather or the like. This seat 6 is supported (and secured as by nails) adjacent its lateral side edges by a pair of forwardly-rearwardly extending comparatively rigid members or bars 8 mounted adjacent their corresponding ends—i. e., their forward ends—so that they may swing inwardly, i. e. toward each other, under the weight of the occupant of the chair. These members 8 may be of various forms and may be thus swingably mounted in various ways, some of which forms and ways being shown in the drawing. In Figures 9 and 12 these members are pivotally mounted on vertical pintle pins 9 carried by metal plates 10 secured as by nails on the lateral side rails 3 of the chair, while in Figure 13 these members 8¹ are mounted on leaf springs 11 disposed edge up and down and secured to the cross rails 3¹.

Various means for yieldingly resisting the inwardly swinging movement of these elongated members may be employed, some of which are shown in the drawing. In Figure 12 coiled springs indicated at 12 are employed pressing between the side rails 3 and the free rear ends of said members, such springs being also shown at 12¹ in Figure 14.

In Figure 13 the leaf springs 11 themselves provide this yielding resistance to the inwardly swinging movement of the elongated members 8¹, and in addition, coiled springs indicated at 12² like that shown in Figure 14 may be employed pressing between the lateral side rails 3¹ and the inner free ends of said members 8¹.

In the modified construction shown in Figure 13 the leaf springs 11 have a slight torsional flexure so that the members 8¹ carried thereby

swing not only inwardly but somewhat downwardly, wherefore the axis of the coiled springs 12² is inclined somewhat inwardly-downwardly. The inner ends of said springs are shown pressing against the brackets 14 mounted on the inner side of said cross rails 3¹.

It will be seen that the weight of the occupant presses and bows downwardly the flexible seat 6 increasingly toward the rear of the chair and 10 the free rear ends of the elongated members as indicated in Figures 10 and 11.

The chair's back 7 is also a flexible sheet member supported adjacent its lateral side edges by elongated comparatively rigid members extending 15 upwardly-downwardly. In order that this flexible back may conform to the back of the occupant (indicated by dotted line 15 in Figure 1), a pair of such elongated members are provided seated in a rabbet 16 in the forward outer corner 20 of each of the leg posts 1 of the chair. The members 8², 8³ of each of these pairs are suitably mounted adjacent their mutually adjacent ends for inwardly-swinging movement under the pressure of the back of the occupant, being thus 25 mounted in the illustrated construction by pintle pins 17, 18 carried by the metallic members 19 secured as by nails to the leg posts.

Such mounting is so vertically positioned as to 30 correspond with the "hollow" of the back of the occupant as indicated in Figure 1. The inwardly-swinging movement of these elongated members 8², 8³ is yieldingly resisted by suitable means as the coiled springs 12³, 12⁴ pressing between the leg posts 1 and the free ends of said members as 35 shown in Figures 3 and 4. A pair of upwardly-downwardly extending comparatively rigid members 8⁴ on which the upper portion of the back 7 is supported adjacent its lateral edges respectively are hingedly mounted at 20 on the upper 40 ends of the members 8³ respectively for inwardly swinging movement to positions in which they may be stopped by stops 21.

As indicated in some of the views, the flexible seat and back members 6, 7 may be arranged to 45 slidably bear on lateral side portions of the base or frame of the chair in the swinging movement of the elongated members.

Means for adjusting the tension of any of the coiled springs is shown in Figure 14, in which the 50 threaded bolt 22 slidably mounted in the lateral side rail or rear post 23 of the chair and abutting at its end 24 against the swingable elongated member 25, carries a nut 26 between which and said base member the coiled spring 12¹ presses.

55 The invention being intended to be pointed out in the claims, is not to be limited to or by details of construction and arrangement of any particular embodiment thereof illustrated by the drawing or hereinbefore described.

60 I claim:

1. In a chair, in combination: a base; a yielding support for the occupant comprising a flexible sheet member and a pair of elongated comparatively rigid members extending approximately 65 parallelly with the lateral sides of the chair, in

supporting relation with the sheet member adjacent its lateral edges parallel therewith and pivotally mounted at one end for yielding inwardly swinging movement.

2. In a chair, in combination: a base; a yielding support for the occupant comprising a flexible sheet member and a pair of elongated comparatively rigid members extending approximately parallelly with the lateral sides of the chair, in supporting relation with the sheet member adjacent its lateral edges parallel therewith and pivotally mounted at one end for inwardly swinging movement, and springs adjacent the free ends of the elongated members for yieldingly resisting said movement.

3. In a chair, in combination: a base; a yielding support for the occupant comprising a flexible sheet member and a pair of elongated comparatively rigid members extending approximately parallelly with the lateral sides of the chair, in supporting relation with the sheet member adjacent its lateral edges parallel therewith, and a pair of leaf springs mounted on the base adjacent its lateral sides, the elongated members being pivotally mounted at one end on the sides of said springs respectively for inwardly swinging movement against the pressure of said springs.

4. In a chair, in combination: a base; a yielding support for the occupant comprising a flexible sheet member and a pair of elongated comparatively rigid members extending approximately parallelly with the lateral sides of the chair, in supporting relation with the sheet member adjacent its lateral edges parallel therewith, and a pair of springs mounted on the base adjacent its lateral sides, the elongated members being pivotally mounted at one end on said springs respectively for inwardly swinging movement against the pressure of said springs.

5. In a chair, in combination: a base; a yielding support for the occupant comprising a flexible sheet member and a pair of elongated comparatively rigid members extending approximately parallelly with the lateral sides of the chair, in supporting relation with the sheet member adjacent its lateral edges parallel therewith and pivotally mounted at one end for yielding inwardly swinging movement, the sheet member bearing in said movement on the base adjacent the elongated members.

6. In a chair, in combination: a base; a yielding support for the occupant comprising a flexible sheet member and a pair of elongated comparatively rigid members extending approximately parallelly with the lateral sides of the chair in supporting relation with the sheet member adjacent its lateral edges respectively, said elongated members being mounted on the chair frame for an inwardly swinging pivotal movement permitting different degrees of depression of said sheet member at different portions thereof; and spring means for yieldingly resisting said inwardly swinging movement.
